HENRY JUIESE EIFLER AND GUSTAVE ADOLPH NAUMAN, OF OXNARD, CALIFORNIA.

DRAFT AND STEERING DEVICE.

SPECIFICATION forming part of Letters Patent No. 731,875, dated June 23, 1903.

Application filed February 3, 1903. Serial No. 141,656. (No model.)

To all whom it may concern:

Be it known that we, HENRY JUIESE EIFLER and GUSTAVE ADOLPH NAUMAN, citizens of the United States, and residents of Oxnard, 5 in the county of Ventura and State of California, have invented a new and Improved Draft and Steering Device, of which the following is a full, clear, and exact description.

This invention relates to improvements in 10 draft and steering devices for plows and similar implements in the use of which a straight course is desired—such, for instance, as in plowing up beets—the object being to provide a draft and steering mechanism so connected to a plow that the plow-beam is relieved of all strain except a slight lateral strain, thus making it more durable, and, further, to so arrange the steering mechanism that the steering may be accomplished by 15 very little manual exertion.

We will describe a draft and steering device embodying our invention and then point out the novel features in the appended claim.

Reference is to be had to the accompanying 25 drawings, forming a part of this specification, in which similar characters of reference indicate corresponding parts in all the figures.

Figure 1 is a perspective view of a portion of a plow with a draft and steering device 30 embodying our invention attached thereto. Fig. 2 is a side elevation thereof; and Fig. 3 is an inverted plan view, partly in section, on the line 3 3 of Fig. 2.

Referring to the drawings, 5 designates the 35 plow-point, 6 the standard, and 7 the beam. A draft-rod 8 has swinging connection with the beam by means of a clevis 9. This draft-rod extends along and underneath the beam, and its forward end is supported in a loop 10, 40 adjustably connected to the forward end of the plow-beam.

As here shown, the upwardly-disposed members of the loop are slotted to receive a clamping-bolt 11, which passes through the beam. 45 A double crank has swinging connection with the forward end of the beam. This crank

consists of a vertical portion 12, having bearings in plates 13 14, extended laterally from the beam, and the lower member 15 of the crank is connected, by means of a link 16, 50 with the draft-rod 8. The draft-rod is provided with a series of holes, as is also the lower member 15 of the crank, so that the leverage may be adjusted by shifting the link 16. From the upper member 17 of the double 55 crank a shifting rod 18 extends to a lever 19, pivoted on the rear end of the beam. The upper member 17 of the crank is also provided with a series of holes, so that the rod 18 may be adjusted to or from the vertical 60 portion 12. By this construction there is comparatively little strain on the plow-beam, and by means of the lever 19 the draft-rod may be quickly shifted, so as to bring the plow into the desired course, and it is obvious that 65 by placing the operating mechanism near the forward end of the draft-rod very little manual exertion will be required to shift it.

Having thus described our invention, we claim as new and desire to secure by Letters 70 Patent—

In a plow or similar implement, the combination with a beam and standard of a draft-rod having vertical and horizontal swinging connection with the standard below the beam, 75 an adjustable loop on the forward end of the beam through which said rod passes, plates extended laterally from the forward end of the beam, a double crank having bearings in said plates, a link connection between the 80 lower member of the crank and the draft-rod, a lever at the rear portion of the beam, and a rod connection between said lever and the upper member of the crank.

In testimony whereof we have signed our 85 names to this specification in the presence of two subscribing witnesses.

HENRY JUIESE EIFLER.

GUSTAVE ADOLPH NAUMAN.
